UNITED STATES PATENT OFFICE.

ALFRED QUADE AND ARTHUR H. KLUMB, OF WEST BEND, WISCONSIN, ASSIGNEES TO
WEST BEND EQUIPMENT CORPORATION, OF WEST BEND, WISCONSIN, A CORPORA-
TION OF WISCONSIN.

STANCHION.

Application filed May 28, 1925. Serial No. 33,360.

This invention relates to stanchions and the object of the invention is to improve the construction and operation of stanchions in the manner to be hereinafter described 5 and claimed.

Referring to the drawings which accompany this specification and form a part hereof, which drawings illustrate an embodiment of this invention, and on which drawings the same reference characters are used to designate the same parts, Fig. 1 is an elevation of a stanchion and part of a stall, the stanchion being shown in its closed position; Fig. 2 is a view similar to Fig. 1 15 but showing parts occupying different positions from the positions which they are shown occupying in Fig. 1; Fig. 3 is a vertical section of parts of the mechanism; Fig. 4 is an elevation of parts of the mechanism looking in the direction indicated by the arrow 4 on Fig. 1 of the drawings; Fig. 5 is a section taken on the line 5—5 on Fig. 1 of the drawings, looking in the direction indicated by the arrows; Fig. 6 is a plan 20 view of parts of the apparatus; Fig. 7 is a perspective view of a part; and Fig. 8 is a section of parts of the mechanism taken on the line 8—8 on Fig. 2 of the drawings, looking in the direction indicated by the 25 arrows.

Referring to the drawings, the reference numeral 1 designates uprights of a stall and these uprights are illustrated by the drawings as secured in place by clamps 2 which are secured in cement or concrete 3. The uprights 1 are secured by clamps 4 to a top rail 5 and are provided with side rails or partitions 6. The clamps 4 also support and guide an operating rod 7, which may be either a solid rod or a piece of pipe, for operating movable sure stops 8 which are located between the fixed bows 9 of stanchions and the adjacent uprights 1. It will be understood, of course, that a number of stalls are arranged in alinement and that the operating rod 7 operates the movable sure stops 8 for a plurality of stalls. The movable sure stops 8 are provided with crank arms 10 and 11 at their tops and bottoms and the upper crank arms 10 are pivoted on pivots 12 which are secured to the top rail 5 by clamps 13. The lower crank arms 11 are pivoted upon pivots 14 which extend upwardly from anchors 15 secured in the

cement or concrete 3. The pivots 12 and 14 for a movable sure stop 8 are in line with each other and the gear 16 is secured to an upper crank arm 10 and meshes with a rack 17 which is secured to the operating rod 7. It will be readily understood that, by reciprocating the operating rod 7, a plurality of movable sure stops can be actuated in unison and that each movable sure stop may be moved through an arc of 180° from a position close to an adjacent upright 1 to a position substantially midway between that upright 1 and the fixed bow of the stanchion, or from the latter position to the former position. The movable bow of a stanchion is designated by the reference numeral 18 and between the movable bow of the stanchion and the adjacent upright 1, a fixed sure stop 19 is provided.

A stanchion is designated, for convenience of reference, by the reference numeral 20 and its fixed and movable bows may be constructed from pieces of channel iron 21 and 22, with the channels opening outwardly, and with pieces of wood or other suitable material 23 and 24 secured to the insides thereof. The channel iron 21 of the fixed bow 9 is illustrated by the drawings as bent at each end to provide substantially parallel horizontal top and bottom members 25 and 26.

The stanchion is hung from the top rail 5, in a manner to be hereinafter described, in such a manner that, when closed, it is held in a fixed position, at its top, both longitudinally and laterally with respect to a stall while its lower end is free to be moved to a limited extent both longitudinally and laterally with respect to a stall. A clamp 27, which is of an inverted U-shaped form, is clamped, by a single bolt 28, upon the bottom member 26 of the channel iron 21 of the fixed bow 9, and a flexible member, such as the loose chain 29, is connected to the bolt 28 and to a ring member 30 which is adjustably secured by a nut 31 to an anchor 32 which is set in the cement or concrete 3. The clamp 27 is provided with inwardly projecting shoulders 33 and 34 which are substantially parallel with the outstanding edges of the channel iron 21 and which, while so close to the edges of the channel iron that rocking of the clamp 27 is substantially prevented, are free enough so that

the clamp may be moved freely back and forth upon the bottom member 26 when the nut on the bolt 28 is loosened. By using a clamp which is provided with means for preventing its rocking, such as the shoulders 33 and 34 or an equivalent construction, one bolt is all that is necessary to secure a clamp in position, it being understood, of course, that the purpose is to hold a clamp firmly in position upon a channel iron without having to set a bolt up so tight that the channel iron would be mutilated. A hinge member 35 is secured to the channel iron 22 of the movable bow 18 by rivets 36, or other suitable fastening means, and a hinge pin 37 connects the hinge member 35 with a hinge member 38 which is adjustably secured in place upon the bottom member 26 of the fixed bow 9 by a bolt 39. The hinge member 38 is provided with shoulders 40 and 41 to prevent its rocking upon the bottom member 26 of the fixed bow 9, as heretofore described in connection with the clamp 27. The hinge member 35, the hinge pin 37, and the hinge member 38 constitute a hinge 42 for hinging the movable or swinging bow 18 to the fixed bow 9 by an adjustable hinge connection, as, by loosening the nut 43 on the bolt 39, the distance between the fixed bow 9 and the movable or swinging bow 18 can be increased or decreased to suit the size of the neck of the animal which is to be secured in the stanchion. A stop 44 is adjustably secured to the top member 25 of the fixed bow 9 and can be positioned by means of the bolt 45 to correspond with the position of the hinge 42 on the bottom member 26 so that the movable or swinging bow 18 will be, when closed, substantially parallel with the vertical part of the fixed bow 9. It will be understood, of course, that, when the distance between the bows has been changed, the clamp 27 and the upper clamp 46 will be shifted or adjusted to positions about midway between the bows, when the movable or swinging bow is closed. The upper clamp 46 is illustrated as provided with a hollow cylindrical upper part 47 with a closed top provided with a hole 48 for a suspension bolt 49. The hole 48 is sufficiently large to permit the upper clamp 46, and consequently the stanchion 20, to swing freely in any direction to the extent permitted by the flexible member or chain 29. The upper clamp 46 is also illustrated as provided with oppositely disposed lugs 50 and 51 extending outwardly from the cylindrical part 47, and a ring 52 is provided with oppositely disposed notches 53 to engage with the lugs 50 and 51 to prevent the stanchion from being turned. The upper clamp 46 is clamped to the top member 25 of the fixed bow 9 by means of a bolt 54 and the cylindrical part 47 is provided with

a passage way 55 for a cam 56 of a link 57 which is freely slidable in the channel 58 of the channel iron 21 and through the passageway 55. When the movable or swinging bow 18 is closed, the cam 56 should be high enough to lift the ring 52 clear of the lugs 50 and 51, so that the stanchion can swing freely, and the cam 56 should be so positioned on the link 57 that when the movable or swinging bow 18 is open, the ring 52 will not be supported by the cam 56 and can drop to a position where the lugs 50 and 51 will be received in the notches 53 on the ring to prevent the stanchion from being turned. The ring 52 is prevented from turning movement by projections 59 and 60 which extend between the parts 61 and 62 of the hanger 63 which is secured to the top rail 5 by a cap 64 and bolts 65.

The link 57 is pivoted by a bolt or pivot 66 to an extension 67 which is secured against the channel iron 22 of the swinging or movable bow 18 by a bolt 68, and which has a lip 69 extending into the channel of the channel iron 22 to serve as an abutment for a spring 70 which presses a latch 71 upwardly to engage behind a catch 72 formed as a part of the stop 44. The catch 72 is bevelled or rounded on its outer side and the inner side of the top of the latch 71 is rounded, as designated by the reference numeral 73, to co-act, in fastening, with the rounded part 74 of the catch 72. The bolt 68 passes through a slot 75 in the latch 71 and a projection 76 extends from the latch 71 through a slot 77 in the extension 67.

The link 57 is provided with a knob or stop 78 on its free end which can contact with the stops 79 and 80 on the stop 44 to limit the extent of the swinging or opening movement of the movable or swinging bow 18 of the stanchion. The knob or stop 78 is illustrated by the drawings as small enough to slide through the channel 58 of the top member 25 of the channel iron 21 of the fixed bow 9 and any suitable means or construction may be provided to prevent disengagement of the parts. The drawings illustrate the link 57 as provided with a stop 81 adapted to contact with the extension 67 to limit the upward extent of movement of the free end of the link 57 so that the knob or stop 78 will not rise above the stops 79 and 80.

The ring member 30 can be adjusted, by means of the nut 31, longitudinally of the stall to provide for the length of a cow and the top of the stanchion can be correspondingly adjusted longitudinally of the stall by loosening the nuts 82 on the bolts 65 and moving the hanger 63 longitudinally of the stall. The hanger 63 is secured by the bolts 65 against the bottom of a lower cap mem-

ber 83. A notched plate 84 removably fits into the part 61 of the hanger 63 and is retained in place by the pivoted latch 85. The latch 85 can be swung up on its pivot 86 free of the notched plate 84 and the notched plate 84 can then be slid out far enough to be free from the suspension bolt 49 and the top of the stanchion can be moved to another position longitudinally of the stall. The notched plate 84 can then be pushed back and the latch 85 lowered to retain it in place. It will be readily understood, from an inspection of Fig. 3 of the drawings, that the suspension bolt 49 bears against a flange 87 on the part 62 of the hanger 63 and the notched plate 84 and that the nut 88 on the suspension bolt 49 supports the stanchion by resting upon the flange 87 and the notched plate 84.

20 The stop 44 is provided with shoulders 89 and 90 which project over the edges of the flanges of the top member 25 of the channel iron 21 of the fixed bow 9 to prevent rocking of the stop 44 which is held in position by the single bolt 45.

25 The construction and operation, and the principles of construction and operation of the stanchion are obvious from the foregoing description taken in connection with the drawings. The movable sure stops 8 are intended to be moved into position adjacent the fixed bows of the stanchions, when the stanchions are to be opened, and to be moved back away from the stanchions when the stanchions are to be closed. The movable sure stops 8 and the fixed sure stops 19 thus block the fronts of stalls in a well-known manner. The fixed and the movable or swinging bows of the stanchions also act as sure stops to block the fronts of stalls when the stanchions are opened because the rings 52, when released from the cams 56, drop down and engage the lugs 50 and 51, on the upper clamp 46, within the notches 53 and the projections 59 and 60 prevent the turning of a ring and its stanchion.

30 What we claim is:

1. The combination with a stanchion, of a plurality of coacting members for suspending the stanchion and permitting rotational movements thereof, and a vertically movable, non-rotatable member, independent of the stanchion but adapted to coact therewith to prevent rotational movement of the stanchion.

2. The combination with a stanchion, of a plurality of coacting members for suspending the stanchion for rotational movements, and a vertically movable, non-rotatable ring member independent of the stanchion but adapted to coact therewith to prevent rotational movements thereof.

3. The combination with a stanchion comprising a fixed bow and a movable bow, of

a stationary member and a member secured 65 to the stanchion but rotatable with respect to said stationary member for suspending the stanchion to permit rotational movements thereof, a member connecting the fixed bow and the movable bow and provided with 70 a cam, and a vertically movable, non-rotatable member, adapted to be positioned by movements of said cam into positions of engagement or disengagement with said stanchion. 75

4. The combination with a stanchion comprising a fixed bow and a movable bow, of means for suspending the stanchion, vertically movable locking means upon the means for suspending the stanchion to prevent rotation of the stanchion, a latch connecting the fixed bow and the movable bow and adapted to control said locking means so that the stanchion can be rotated when the movable bow is closed while the opening of 85 the movable bow causes the stanchion to be locked against rotation.

5. The combination with a stanchion comprising a fixed bow with substantially horizontal top and bottom members and a movable bow hinged to the bottom member, of means for rotatably suspending the stanchion, a non-rotatable locking member surrounding said means for rotatably suspending the stanchion, and means connecting the fixed bow and the movable bow and adapted to determine the position of said locking member. 90

6. The combination with a stanchion comprising a fixed bow and a movable bow hinged together at their lower ends and the fixed bow being provided with a substantially horizontal top member of channel iron with the channel opened outwardly, of locking means to lock the two bows together, means for rotatably supporting the stanchion, a vertically movable but non-rotatable member adapted to prevent the rotation of the stanchion, a link pivotally connected to the movable bow and extending through the channel of the channel iron of the top member of the fixed bow and provided with a stop to limit the extent of opening movement of the movable bow and also provided with a cam to lift said non-rotatable locking member out of engagement with the stanchion when the movable bow is closed. 105

7. The combination with a stanchion, of a hanger for supporting the stanchion, said hanger being provided with a removable notched plate, a latch for retaining said notched plate in position in the hanger, and means positioned by said notched plate for supporting the stanchion. 115

120 In witness whereof we hereto affix our signatures.

ALFRED QUADE.
ARTHUR H. KLUMB.
